CHECK PROTECTOR

Harvey L. Hager, Paradise, Calif., assignor of two-thirds to Harvey L. Hager, Jr., Miami, Fla.
Filed Aug. 31, 1961, Ser. No. 135,226
3 Claims. (Cl. 101—24)

This invention relates to a check protector and has as its primary object the provision of a hand manipulable device which may be actuated to create a series or band of minute perforations through the figures designating the amount of a check in order to prevent alteration of the check.

An additional object of the invention is the provision of a device of this character which is small in size, and which may be readily operated by hand, comprising a pair of spaced apart rods together with means for clamping the ends of the rods on the opposite faces of the check to be protected, one of the rods being provided with a steel roller having a series of teeth therein, and the other of the rods being provided with preferably a rubber roller, together with means for rotating one of the rods to imprint the perforations in the paper of the check.

A further object of the invention is the provision of a device of this character which is sturdy and durable in construction, reliable and efficient in operation, and relatively simple and inexpensive to manufacture.

Other objects will in part be obvious and in part be pointed out as the description of the invention proceeds and shown in the accompanying drawing wherein:

FIGURE 1 is a top plan view of one form of the device embodying the instant inventive concept, showing a check to be protected in position therein.

FIGURE 2 is a sectional view taken substantially along the line 2—2 of FIG. 1 as viewed in the direction indicated by the arrows.

FIGURE 3 is an enlarged sectional view taken substantially along the line 3—3 of FIG. 1 as viewed in the direction indicated by the arrows.

FIGURE 4 is a fragmentary enlarged view, partially in section and partially in elevation, showing a constructional detail.

FIGURE 5 is a view similar to FIG. 1 showing a modified form of construction, the fragment of the check being omitted.

FIGURE 6 is a sectional view taken substantially along the line 6—6 of FIG. 5 as viewed in the direction indicated by the arrows; and

FIGURE 7 is an enlarged sectional view taken substantially along the line 7—7 of FIG. 5 as viewed in the direction indicated by the arrows.

Similar reference characters refer to similar parts throughout the several views of the drawing.

Having reference now to the drawings in detail, and more particularly to the form of the invention disclosed in FIGS. 1 to 4, the device of the instant invention is generally indicated at 10 and comprises a first rod or bar 11, which is preferably solid in construction and which terminates in a shaft or axle 12 upon which is mounted a roller 13, greater in diameter than the rod 12, and preferably comprised of rubber or similar material. The head of the axle 12 is peened as at 14 and secures in position a washer 15 which holds the roller 13 in position.

A U-shaped yoke 16 is pivotally connected as by means of a pivot 17 at one corner thereof to an intermediate point of rod 11. Passing through the bight of yoke 16 is a tubular shaft 18, which has a rod 19 extending rotatably therethrough, the rod 19 terminating at one end in a shaft or axle 20 upon which is mounted a roller 21 which is preferably of steel or similar construction, and which is provided about its periphery with a series of perforating

2

teeth 22, the rollers 13 and 21 being in substantial alignment, so that when they are pressed together with a check C or similar article positioned between them, rotation of the rod 19, in a manner to be described hereinafter, will cause the teeth 22 to impart perforations P through the material of the check and protect the figures or other matter written thereon from possible alteration.

Rotation of the shaft 19 is effected by means of a knurled hand knob 23 positioned on the end thereof opposite the roller 22 and extending beyond the end of the yoke 16.

Means are provided for clamping the rollers 13 and 22 tightly upon the opposite faces of the check and take the form of a cam shaft or eccentric 25 which is journaled in the opposite sides of the yoke 16, and which includes a flat surface 26. A washer 27 and a peened head 28 secure one end of the eccentric 25 for rotation while the other end is provided with a head 29 from which extends an operating lever 30. The arrangement is such that when the cam 25 in the position shown in FIG. 2, for example, the end 31 of rod 11 beyond the pivot 17 is rotated to clamp the roller 13 relatively tightly on the face of the check C adjacent the roller 22. Separation of the members is effected by juxtaposing the flat surface 26 to either the rod 11 or the tubular member 18, to permit separation of the rollers and the introduction of the check or other material therebetween. After the check has been clamped, the knob 23 is rotated, and the teeth 22 impart the perforations P as shown in FIG. 1.

A modified form of device is disclosed in FIGS. 5, 6, and 7, and comprises a bar or rod 35, which has an axle 36 at one end upon which is mounted a rubber roller 37 substantially identical to the roller 13, the latter being held in position by means of a peened end 38 of axle 36 and the washer 39. A yoke 40 similar to the yoke 16 is pivotally mounted on a pivot 41 extending through the rod 35, and a tubular member 42 seats in the bight of the yoke 40. The shaft 43 extends through the tubular member 42 and carries an axle 44 at one end upon which is mounted a steel roller 45 having teeth 46 substantially identical to the roller 21. The head of the axle 44 is peened as at 47 to secure the roller in position, and a knurled operating knob 48 at the opposite end permits rotation of the shaft to 43. Adjustment in this device is achieved by means of a set screw 49 which extends through a threaded bore in the end 50 of shaft 35 and which is operated by a knurled operating knob 51. Obviously, adjustment of the set screw 49 will permit separation of the rollers 37 and 45, or alternatively, clamp them tightly together on the opposite faces of a check. The operation of this form of the device is identical in other respects to that of the previously described modification.

From the foregoing it will now be seen that there is herein provided an improved check protector, which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative, and not in a limiting sense.

I claim:

1. In a check protector, the combination of a first rod, a roller at one end thereof, a yoke, a tubular member secured in the bight of said yoke, a second rod rotatable in said tubular member, a toothed roller at the end of said second rod aligned with said first roller, a pivot pin extending through an intermediate point of said first rod and extending between the arms of said yoke spaced from said tubular member, means to pivot said first rod selectively

to separate said roller and said toothed roller to permit the insertion of a check therebetween and clamp said roller and said toothed roller together on opposite sides of a check, and a knurled knob carried by the end of said second rod opposite said toothed roller to rotate said second rod to rotate said toothed roller to impart a band of perforations to said check.

2. In a check protector, the combination of a first rod, a roller at one end thereof, a yoke, a tubular member secured in the bight of said yoke, a second rod rotatable in said tubular member, a toothed roller at the end of said second rod aligned with said first roller, a pivot pin extending through an intermediate point of said first rod and extending between the arms of said yoke spaced from said tubular member, means to pivot said first rod selectively to separate said roller and said toothed roller to permit the insertion of a check therebetween and clamp said roller and said toothed roller together on opposite sides of a check, and a knurled knob carried by the end of said second rod opposite said toothed roller to rotate said second rod to rotate said toothed roller to impart a band of perforations to said check, said means for separating and clamping said rollers comprising an eccentric journaled in said yoke and extending between said first rod and said tubular member, and lever means for rotating said eccentric.

3. In a check protector, the combination of a first rod, a roller at one end thereof, a yoke, a tubular member secured in the bight of said yoke, a second rod rotatable in said tubular member, a toothed roller at the end of said second rod aligned with said first roller, a pivot pin extending through an intermediate point of said first rod and extending between the arms of said yoke spaced from said tubular member, means to pivot said first rod selectively to separate said roller and said toothed roller to permit the insertion of a check therebetween and clamp said roller and said toothed roller together on opposite sides of a check, and a knurled knob carried by the end of said second rod opposite said toothed roller to rotate said second rod to rotate said toothed roller to impart a band of perforations to said check, said means for separating and clamping said rollers comprising a set screw extended through a threaded bore in said first rod and abutting said tubular member.
